Benjamin Axel, Brooklyn, N. Y., assignor to Axel Brothers, Inc., New York, N. Y.

Application May 16, 1938, Serial No. 77,212

Term of patent 3½ years

To all whom it may concern:

Be it known that I, Benjamin Axel, a citizen of the United States, residing at Brooklyn, New York, have invented a new, original, and ornamental Design for a Watch Bracelet or Similar Article, of which the following is a specification, reference being had to the accompanying drawing, forming a part thereof.

showing my new design.

Fig. 2 is a side edge view thereof.

I claim:

The ornamental design for a watch bracelet or similar article, as shown.
